UNITED STATES PATENT OFFICE.

ALEXANDER SAMUEL BERMAN, OF PHILADELPHIA, PENNSYLVANIA.

MAN'S SHIRT.

1,326,472.

Specification of Letters Patent. Patented Dec. 30, 1919.

Application filed November 23, 1916. Serial No. 132,954.

To all whom it may concern:

Be it known that I, ALEXANDER S. BERMAN, a citizen of the United States, and a resident of Philadelphia, in the county of 5 Philadelphia and State of Pennsylvania, have invented certain new and useful Improvements in Men's Shirts, of which the following is a specification.

This invention relates to an improvement 10 in men's shirts having flexible cuffs.

Men's shirts having sleeves with flexible cuffs have come greatly into vogue, due especially to the increased comfort they give in warm weather, they being much easier on 15 the wearer's wrists because of the softness of the material. But the increased comfort thus afforded by them is largely offset by a large increase in cost due to the following considerations:

20 Experience has shown that these flexible cuffs get soiled very readily, especially at and near the folded edge. Therefore, although the shirt is otherwise clean and perfectly fit for longer wear, it has to be 25 changed for another due to the unsightly appearance of the cuffs. This increases materially the cost of laundering these shirts, and decreases their effective life, as too frequent laundering, as is well known, is 30 very destructive of the material. Due to the necessity for frequent changes, a larger supply of shirts must be maintained.

Experience has further shown that these flexible cuffs fray at the folded edges after 35 short wear, and although the shirt is otherwise whole, it has to be discarded because of the torn cuffs.

A further disadvantage of these shirts with flexible cuffs arises especially in very 40 warm weather or when the wearer is engaged in work which would increase the liability of the cuffs to get dirty, or which might be interfered with materially by them. The wearer has in such cases resorted to the 45 expedient of rolling up the sleeves. This expedient while effective is not very efficient, inasmuch as much discomfort and annoyance is caused by the increased pressure on the arms of the rolled up portion or by the 50 tendency of the latter to roll or slip down again.

The main object, therefore, of this invention is to provide a man's shirt which shall retain all the advantages of comfort afforded 55 by shirts with flexible cuffs, but which shall at the same time do away with all the dis-

advantages enumerated above without any substantial increase in cost.

The difficulties experienced with men's shirts of the character referred to arise 60 chiefly from the fact that the flexible cuffs are integral with the sleeve. Therefore, to accomplish the object set forth above, I provide a shirt with cuffless sleeves and separate flexible cuffs adapted to be removably 65 attached thereto in a simple and easy manner.

Further objects and advantages will be clear from the detailed description and the features of novelty will be particularly 70 pointed out in the claims.

In the accompanying drawing, forming a part of this specification—

Figure 1 is a vertical elevation of an unfolded shirt sleeve with modified means for 75 attaching the flexible cuff thereto, and Fig. 2 is a perspective view of the corresponding unfolded cuff.

Fig. 3 shows another modified form of sleeve, and Fig. 4 is a part perspective view 80 of a correspondingly modified cuff.

Referring particularly to the drawings, 10 is the improved cuffless sleeve and 11 a flexible cuff adapted to be removably attached thereto. The means for attaching 85 the cuff will now be described.

As will be seen from the drawing, the lower end of the sleeve is provided with a narrow band portion 12.

For attaching the cuff, I provide a separate sleeve band 13' which is removably held to the band 12 of the sleeve by means of flexible straps 19 stitched to the lower portion of the sleeve band 14' carrying sockets 15, is in a like manner held to the inner surface 95 of the cuff by a corresponding set of cuffs 20 attached thereto. The sleeve band 13' is attached thereto, the projection 16 of snap fasteners adapted to enter into these sockets 15 as will be readily understood. 100

In laundering, the bands 13' and 14' may be easily removed by slipping them out of the straps 19 and 20 respectively in the same manner as a belt, and the sleeves and cuffs then present an entirely soft and smooth 105 surface to the press iron.

In the modified form shown in Figs. 3 and 4, I accomplish this same purpose of facilitating the laundering of the shirt, but the straps 19 and 20 of the embodiment of my 110 invention shown in Figs. 1 and 2 are replaced by the flexible strips 21 and 22

stitched respectively to the lower portion of the sleeves and the inner surface of the cuff. These strips have the eyes or openings 23 through which the snap fasteners may be locked. The locking members of the snap fasteners are thus exposed in operative relation through the eyes 23 only to the extent necessary for the proper locking of the snap fasteners. The latter are thus less likely to unbutton and the cuffs are more securely held to the sleeves. The bands carrying the respective members of the snap fasteners may be made in long tapes to which the members are secured in some suitable machine and then cut into lengths corresponding to the various sizes of cuffs.

It will thus be clear that I have provided a man's shirt which retains all the advantages of comfort afforded by the ordinary shirt with soft cuffs, but which gives better wear and is much more economical. In purchasing one of my improved shirts, the customer may at very slight cost provide himself with several pairs of cuffs to match the shirt. When the particular pair of cuffs worn with the shirt becomes dirty, torn or frayed, he may easily detach them and replace them by others which he may attach to the same shirt. The fraying of the cuffs does not necessitate the discarding of the whole shirt as is the case with the shirts hitherto made having flexible cuffs.

Should the wearer wish to get increased comfort in very warm weather, or prevent the cuffs from hindering him in his particular work, or from getting dirty while doing work in which they are very liable to get soiled, he may simply unbutton the cuffs from the sleeves and remove them. When the cuff is removed, the sleeve is left open and may be quickly rolled, if desired.

Having thus described my invention, what I claim as new and desire to secure by Letters Patent is:—

1. In a shirt, a pair of cuffless sleeves, a pair of flexible cuffs therefor, means for removably attaching said cuffs, said means comprising a flexible band carrying a plurality of spaced buttons, a similar flexible band carrying a plurality of correspondingly spaced sockets for the buttons, means on the lower portion of the sleeves for removably holding the first mentioned button band thereto, and means on the inner surface of the cuffs adjacent the upper edge thereof for removably holding the last mentioned socket band.

2. In a shirt, a pair of cuffless sleeves, a pair of flexible cuffs therefor, means for removably attaching said cuffs, said means comprising a flexible band carrying a plurality of spaced buttons, a similar flexible band carrying a plurality of correspondingly spaced sockets for the buttons, a plurality of strips attached to the lower portions of the sleeves through which the button band may pass to be removably held on the sleeve, and a plurality of similar holding strips attached on the inner surface of the cuffs adjacent the upper edge thereof for removably holding the socket band on the cuffs, the disposition and configuration of the strip forming open spaces through which the buttons may pass to be locked in the sockets.

Signed at Philadelphia, in the county of Philadelphia and State of Pennsylvania, this 21st day of November, A. D. 1916.

ALEXANDER SAMUEL BERMAN.
